Primary Examiner — Cynthia R Underwood(74) *Attorney, Agent, or Firm* — Eckert Seamans Cherin & Mellott, LLC(57) **CLAIM**

The ornamental design for a cable hanger, as shown and described.

DESCRIPTION

FIG. 1 is a first isometric view of the cable hanger;

FIG. 2 is a second isometric view of the cable hanger;

FIG. 3 is a top view of the cable hanger;

FIG. 4 is a bottom view of the cable hanger;

FIG. 5 is a left view of the cable hanger;

FIG. 6 is a right view of the cable hanger;

FIG. 7 is a back view of the cable hanger; and,

FIG. 8 is a front view of the cable hanger.

The broken lines in the drawings depict environmental subject matter only and form no part of the claimed design.
